United States Patent Office.

MORRIS BOTTICHER, OF NEWARK, NEW JERSEY.

Letters Patent No. 72,595, dated December 24, 1867.

IMPROVEMENT IN STEAM-GAUGES.

The Schedule referred to in these Letters Patent and making part of the same.

TO ALL WHOM IT MAY CONCERN:

Be it known that I, MORRIS BOTTICHER, of Newark, in the county of Essex, in the State of New Jersey, have invented a new and improved Pressure or Vacuum-Gauge; and I do hereby declare that the following is a full and exact description thereof, reference being had to the accompanying drawings, and to the letters of reference marked thereon.

Figure 1 is a vertical section through the centre of gauge.

Figure 2, a front elevation.

The gauge is attached to the pressure or vacuum-chamber by means of the pipe A and nut B. The pressure, passing through the openings C C into the chamber D, comes in contact with the flexible disk E, which is held in its place by passing between the cap F and base G. The cap F and base G are fastened securely together by means of the screws H H', making, in connection with the disk E, a tight joint. The chamber formed by the cap F, above the disk E, is filled with mercury through the opening I, which is closed by the screw J. The screw J is also used for the purpose of adjusting the mercury to its proper height in the glass tube K. The glass tube K is held in its place at the bottom by means of the stuffing-gland L and nut M, and is protected its entire length by means of the metal tube N, having the pressure-scale marked upon it.

When the pressure is admitted to the chamber D, the disk E will be forced up, decreasing the space in the chamber O, and causing the mercury to rise in the tube K, and indicating the pressure per square inch by the aid of the scale N'.

When used for a vacuum-gauge, the tube K will be filled with mercury to a proper height, and being open at the top, when the action of the disk causes the chamber O to be enlarged, the mercury will fall in the tube K.

Claim.

What I claim as my invention, and desire to secure by Letters Patent, is—

The arrangement of the adjustable screw J with cap F of the gauge, substantially as herein described.

MORRIS BOTTICHER.
